APPARATUS FOR TRACING CURVED LINES

David John Witherspoon, New York, N. Y., assignor to Bee-Ko Company, a corporation of New York

Application May 20, 1937, Serial No. 143,680

1. Claim. (Cl. 33—31)

This invention comprises novel mechanism for tracing elliptical and other outlines which shall have a predetermined curvature of mathematical exactness.

5 The preferred form of apparatus embodying my invention is primarily designed to trace the outlines of ellipses of different predetermined dimensions, with axes and foci having given locations, by means of a marker carried by a movable or floating member supported by adjustable spaced-apart pivots which are caused to simultaneously reciprocate along lines at right angles one to the other and parallel to and overlying the axes of the desired ellipse. Such rotation causes 10 said floating member to complete one revolution about constantly shifting axes perpendicular to the plane in which said member has its movement of translation, or orbital motion. If, then, a marker lies in a plane in which the axes of both 15 pivots also lie and outside of the space between them, an ellipse will be traced.

The best construction for such apparatus embodying my invention at present known to me is illustrated in the accompanying two sheets 25 of drawings in which.

Fig. 1 is a plan view of the apparatus in position upon a sheet of drawing paper or other plane surface on which the curves are to be traced.

Fig. 2 is a cross section on a vertical plane on 30 line 2—2 of Fig. 1. In this view the apparatus is shown as equipped with a lead for tracing the curved line.

Fig. 3 is an enlarged detail elevation of one end of the main frame, the right hand end as shown 35 in Fig. 1, parts being shown in section.

Fig. 4 is an enlarged detail elevation of the lead carrier shown in Fig. 2, but looking at the same from the rear of Fig. 2.

Fig. 5 is a similar detail of the carrier equipped 40 with a pen for tracing the lines.

Fig. 6 is a detail plan in section of the carrier for the marker taken on line 6—6 of Fig. 2, and

Fig. 7 is a detail side elevation of a modification in which the marker is mounted on the other end 45 of the rod 22, which is assumed to have been shoved to the left, looking at Fig. 2, for this purpose.

Referring to the drawings, the apparatus therein shown comprises the end castings 11, 11, which 50 may be held by thumb tacks 23, 23, on the drawing board or clamped thereto, said castings being rigidly connected together by the parallel rods 4, 4, which serve as guides for the carriage 3 sliding freely thereon. The minor axis of the ellipse 55 to be drawn will lie below and between said rods

with the axis of pivot 5 in the carriage movable back and forth over it as the crank 6 is rotated by handle 7 about such shifting pivot 5. Such motion causes opposite but similar rotation of the flat bar 2, both 6 and 2 being pinned fast on 5 5 (as indicated at 28, 28, in Fig. 2) which is journaled in 3 by ball bearings 24, 24.

Clamp member 9 (Fig. 1) is adjustable lengthwise along rod 2 and can be held in adjusted positions thereon by thumbscrew 10. Said clamp 10 may be supported on a foot member 19 (Fig. 2) which is adjustable on rod 22, which in turn is adjustable in 9. The wheel 29 (which may in some embodiments of my invention be replaced by some other anti-friction device) is journaled 15 in 19 and slides or rolls on the surface of the paper. Pen 31 or lead 4 and its holder are carried on the end of rod 22 which is adjustable endwise in clamp member 9 and can be clamped in adjusted position by setscrew 13. Said clamp is pivotally 20 connected at W (Fig. 1) to the apex of the straight line motion system of links 8, 8b, 8a, 8c, 8d, 8e. The angle apex of link pair 8d, 8e, has a fixed pivot X carried by one of the castings 11, 11, (Fig. 3). The angle apex of pair 8a, 8c, (Fig. 1) is 25 pivotally connected at Y to the end of link 8f which swings freely about a fixed point Z (Fig. 1) also carried by 11.

This straight line motion mechanism is not new per se, having been used for drawing certain 30 curved lines by mounting it in a different way from that here shown and placing a marker at one of its pivoted joints. But its use to compel motion of a member connected to its pivot W along a straight line at right angles to that passing through its pivots X and Y when the latter are fixed as hereinafter described, is, so far as I know, original with me. Any equivalent device which would still compel the pivot W on clamp member 9 to travel in a straight line could be 35 substituted for it in this combination if so arranged as not to interfere with other portions of the mechanism. The main advantages in the use of this system of pivoted links as a substitute for an ordinary fixed, rectilinear, slotted member 40 and suitable pivot-carrying slide movable therein, are two. The pivot joints friction is less than the rectilinear slide friction, while the fixed support for this linkage system is located at one end of guides 4, 4, outside of the orbit of any marker 45 carried by the revolving flat bar or rod 2 and outside the path of other moving parts, thus simplifying the whole supporting construction. The function of the straight line motion mechanism is to compel pivot W to move always and 50 55

only in a path indicated by broken line L—L in Fig. 1 which extends across and at right angles to the line of guides 4, 4'. This line of travel L—L is also the major axis of the ellipse to be drawn when the marker 1 (Fig. 7) or 31 (Fig. 5) is carried at that end of the movable member formed by parts 2, 5, 6, 7, 9 and 22, on which it is shown as being mounted in Figs. 1 and 2 of the drawings.

10 14 (Fig. 1) is a tension spring which is used to maintain the straight line motion linkage under light strains all in the same direction at all its joints at all times so as to take up any slack therein. Otherwise watchmaking precision would 15 be required in fitting all the six pivot joints therein included to prevent the links 8 to 8 from shifting slightly in their relative positions under reversals of operating strains.

20 30 is a pointer adjustably mounted in the lower part of clamp 9 in line with the axis of the pivotal connection W to the straight line motion linkage. Consequently, this pointer will always travel along the major axis of the ellipse when the parts are in motion and a marker located on 25 member 22 as shown in Fig. 2. It is prevented from sticking into or scratching over the paper 25 by the anti-friction support 19 for the left-hand end of rod 22 (looking at Fig. 2) previously described.

30 In the preferred construction of carrier for the marker shown in Figs. 2, 4 and 5 there is a downwardly projecting spindle 32 on the right-hand end of rod 22 (looking at Fig. 2) on which the block 33 is adjustably mounted, being held 35 in position thereon by setscrew 24 (Figs. 2 and 6). Block 33 is also perforated to receive the adjustable supporting member 34 which is held in position by setscrew 35 and has its lower end rounded so as to run smoothly over the paper 25 40 on which it rests. 36 is a swinging member hinged at 37 to block 33 and carrying at its free end either the pencil 1 of Figs. 2, 4 and 6, or the pen 31 of Fig. 5. An upwardly projecting spring finger 38 is supported on block 33, and provided with a small projection 39 adapted to register with a companion depression in the side of the member 36 when the latter is raised so as to lift the pen free of the paper as indicated in 45 broken lines in Fig. 5. As member 36 is turned 50 up so as to bring the middle of spring 40 (Fig. 4) above pivot 37, that also tends to maintain the pen 31 in such raised position. The lead 1 may be clamped in the usual type of split holder 26 which, in turn, is removably held in swinging member 36 by setscrew 27, as best shown in Fig. 4. When 27 is loosened lead holder 26 can be 55 removed and pen 31 (Fig. 5) substituted for it, being also clamped in position by setscrew 27, as shown in Fig. 4. The tension spring 40 (Fig. 4) is connected at one end to hinged member 36 and at the other to swinging member 41 which may be turned on its pivot 44 by handle 42 through an angle of 90 degrees, further swinging motion thereafter being prevented by stop 43. The purpose of this adjustment of tension on spring 40, is to give a greater downward pressure to the lead 1 by turning member 41 into the position shown in Fig. 4 while a lesser pressure is given to pen 31 (Fig. 5) by turning said member 41 up into the 60 position shown in Fig. 5 so as to diminish the tension on the spring 40 and also elevate its anchorage.

As indicated in Fig. 7 the entire marker mechanism carried by the member 32 may be shifted to the lefthand end of rod 22, the latter being

5 moved to the left through the opening for it in the clamp member 9 (looking at Fig. 2). When this is done, if the parts are so arranged that the point of the lead or pen is to the left of the axis of pivot 5 (Fig. 1) the ellipse then traced will have its major axis running at right angles to that of any ellipse which would be traced with the parts in the position shown in Figs. 1 and 2.

To permit the movable, floating structure comprising crank 6, pivot 5, flat strip 2, clamp 9 10 and rod 22 to rotate easily in carriage 3, the ball bearings 24, 24, are provided at either side of the latter as indicated in Fig. 2.

The mode of operation of the apparatus shown in Figs. 1 to 6 may be analyzed as follows:

If pivot 5 and carriage 3 could be held stationary and disconnected from links 8, 8b, revolution of crank 6 would then cause lead 1 to describe a circle about pivot 5, but so long as pin 20 W connecting clamp 9 to the parallel motion mechanism is retained and carriage 3 is free to move on its guides 4, 4', the pivot W forms a shifting center of revolution for the rigid swinging system of elements composed of lead 1 or pen 31 and said elements, whenever the user pushes 25 crank handle 7 around through a closed loop path such as indicated by the arrows A, A, in Fig. 1.

Since pivot 5 moves to the right when crank handle 7 is pushed in the direction of the upper 30 arrows, A, A, and carriage 3 moves in the same direction along guides 4, 4' (all as indicated in broken lines in Fig. 1) while lead 1 swings to the left as indicated by arrows B (and during the return half of the crank handle 7 motion the reverse of the above movements occur) it will 35 be seen that such to-and-fro motion of the shifting pivot center 5 will be progressively lengthening or shortening the effective radius of the "would be" circle (on one side or the other of the ellipse major axis L, L) which lead 1 may be 40 considered as trying to describe around such pivot 5 as a theoretical center, A at any one moment. Consequently, such "would be" circle is thereby squeezed in at each side (as an elastic 45 ring could be deformed into an ellipse by simultaneous opposing side pressures thereon); and the "would be" circle thereby becomes an ellipse B which is traced by the marker on the sheet of paper 25, beneath it.

The length of the major axis of such ellipse 50 obviously is twice the distance from the point of lead 1 to pivot 5, while that of the minor axis is twice the distance from said lead point to pivot W, since said pivot always travels back and forth along the major axis of the ellipse being drawn, at 55 right angles to the line of the guides 4, 4'. If the marker were shifted to the other end of rod 22, as indicated in Fig. 7, the reverse would be true, the ellipse then traced being of the type indicated by arrows A, A.

When clamp 9 is adjusted on member 2 so that point W is beneath pivot 5, the rotation of handle 7 will cause lead 1 to describe a circle the diameter of which is determined by the distance of lead 1 from pivot 5. Such circle would constitute the 60 transition phase through which a series of ellipses like B of gradually decreasing eccentricity might merge into another series like A of gradually increasing eccentricity.

The center of the ellipse in either case coincides 70 with the position occupied by the axis of pivot 5 when the parts are in the position shown in full lines in Fig. 1, that being the point at which the major and minor axes intersect. The broken lines in Fig. 1 show the parts in a position as- 75

sumed when lead 1 is at some point D in the ellipse periphery up to left of the major axis L, L.

The foregoing analysis makes it clear that in setting the preferred form of apparatus here shown, rod 22 should be so adjusted in clamp member 9 that the distance from lead 1 to W is half the minor axis of the desired ellipse, and thereafter clamp member 9 carrying rod 22 with it should be so adjusted on flat bar 2 that the 10 distance from lead 1 to 5 will equal half the major axis of such ellipse.

If the lengths and locations of the axes of any desired ellipse are given, the apparatus should be so placed that the medial line of guides 4, 4' over- 15 lies the major axis while the pointer 30 rests on the minor axis, and the castings 11, 11, then secured in that position by thumb tacks 23, 23. Thereafter the locations of the marker with refer- 20 ence to pointer 30, and that of said pointer with reference to pivot 5, can be properly adjusted as before explained.

Adjustments necessary to draw an ellipse conforming to other given data can be worked out by the user from the principles of operation here- 25 inbefore outlined, or by experiment.

Having described my invention, I claim:

In an apparatus for accurately tracing an ellipse the combination of a main frame provided with a rectilinear guide and means for fastening 30 it in a position such that said guide will extend in

parallel and fixed relation to a plane surface on which such line is to be traced, a movable member provided at one point with pivotal means adapted to slide along said rectilinear guide, and mechanism comprising a swinging straight-line 5 motion-producing device formed of a plurality of links pivoted together and provided with elastic means for maintaining all the pivots thereof continually under a strain in the same general direc- 10 tion sufficient to overpower any normal operative strains in opposite directions exercised thereon, said mechanism being pivoted at one point on said guide and at another point pivoted to said movable member, combined with a marker adjustably mounted on said movable member and 15 adapted to bear on and move over any surface on which said main frame is supported; whereby, when said frame is held in fixed relation to such surface with said marker bearing thereon and said movable member is caused to revolve about 20 the axis of said first mentioned pivotal means, the latter and said second point on said member at which it is pivoted to said straight-line motion-producing device are then severally compelled to travel along their respective rectilinear paths, 25 thereby causing said marker to trace the predetermined ellipse, or portion thereof, on such plane surface.

DAVID JOHN WITHERSPOON. 30
